UNITED STATES PATENT OFFICE.

OSCAR B. ALLGOOD, OF BLOCTON, ALABAMA, ASSIGNOR OF ONE-HALF TO JOHN W. GROVES, OF BIRMINGHAM, ALABAMA.

TRANSFORMER-PROTECTOR.

1,138,170.

Specification of Letters Patent.

Patented May 4, 1915.

Application filed March 11, 1913. Serial No. 753,623.

To all whom it may concern:

Be it known that I, OSCAR B. ALLGOOD, a citizen of the United States, residing at Blocton, in the county of Bibb and State of Alabama, have invented certain new and useful Improvements in Transformer-Protectors, of which the following is a specification.

This invention relates to improvements in transformer protectors and has for its object to provide means whereby a three-phase motor may be prevented from running single phase, thus removing all danger of the transformers being destroyed by an overload.

15 In a three-phase motor circuit fuses are often set at 100 per cent. overload and are very little protection to the transformers and motor. When a fuse is burnt out two transformers are cut off and the motor continues to run single phase and the load is carried by one of the transformers. The motor and transformer will both develop 100 per cent. or more overload, which will soon spoil the transformer and possibly injure the motor.

20 My invention prevents the motor from running single phase by causing the circuit breaker to open the primary circuit whenever a fuse is out.

25 A more specific object of the invention resides in the provision of a plurality of novelly formed solenoids, connected in parallel with the fuses of a three-phase circuit and adapted to operate when one of the 30 fuses is burned out to open the primary circuit.

35 With these and other objects in view, as will become more apparent as the description proceeds, the invention consists in certain novel features of construction, combination, and arrangement of parts, as will be hereinafter described and claimed.

40 For a complete understanding of my invention, reference is to be had to the following description and accompanying drawings, in which,

45 Figure 1 is a transverse sectional view partly in elevation through my invention, showing the same positioned upon the 50 switch board under a circuit breaker and connected in parallel with the fuses. Fig. 2 is a top plan view of my invention, and, Fig. 3 is a transverse sectional view through

the solenoid casing, showing my invention in elevation.

55 Referring in detail to the drawings by numerals, 1 designates a switch board, to which is secured a circuit breaker, generally designated 2, and having the operating lever 3, which is pivotally secured at its lower end.

60 A slotted bar 4 is connected at its forward end to the lever 3 by means of the fastener 5, and is connected at its rear end to an oil switch, not shown.

65 A toggle 6 operates to lock the bar 4 against movement until broken by the member 7. When the toggle is broken, the bar 4 moves upwardly, actuating the oil switch to break the primary circuit through the transformer. I make no claim to the circuit breaker and oil switch but merely show and describe them to illustrate the application of my invention.

70 In the embodiment of my invention, I provide a casing 8, having a top wall 9, said casing being secured to the switch board 1 directly under the circuit breaker by means of the fasteners 10. The casing supports three solenoids, each comprising a 75 preferably brass tube 11, closed at its lower end and provided adjacent its upper end with the flange 12. The tubes project 80 through openings in the bottom of the casing and are supported by means of the collars 13. A coil 14 of asbestos-covered 85 wire encircles that portion of each tube which extends within the casing 8. It will be noted that the flange 12 and collar 13 cooperate with the tube to form a sort of spool upon which the wire is wound. Longitudinally bored tubular members 15 close the 90 upper ends of the tubes and are threaded into engagement with nuts 16, which are mounted in the cover 9 of the casing. Pins 17 having enlarged heads extend through 95 the tubular members 15 and project beyond the inner ends of the same. Cores 18 are slidable within the tubes 11.

100 A bar 19 is pivoted between the brackets 20 by means of a suitable fastener passing through said brackets and projection 21 formed upon said bar. The bar is formed with a plurality of lateral projections 22, which are disposed in the path of the pins 17. The central projection 22 is formed with 105 a longitudinally extending portion 23, to

which is connected a rod 24, said rod being connected at its upper end to the bar 7.

The coils 14 are connected by the wires 25 in parallel with the respective fuses 26, said fuses being in the three-phase line 27, which leads to the motor, not shown.

When the fuses are intact a very small quantity of current will pass through the coils 14, but when a fuse is burnt out, the 10 corresponding coil will be energized and raise the corresponding core 18, which will strike one of the pins 15. This pin will be raised and cause an upward movement of the rod 24, which motion will be transmitted 15 to the member 7 so as to break the toggle 6 and open the primary circuit.

It will be seen from the foregoing description in connection with the accompanying drawings, that I have provided a transformer protector which will protect the transformers in a three-phase circuit from being destroyed by an overload heating the oil, which protects the motor by preventing it from running single phase under an overload, and which, when a fuse is out, indicates the fact should an attempt be made to start the motor.

It is to be understood that I do not wish to be limited to that embodiment of my invention shown herein, but wish to protect the idea of connecting a similar device in parallel with the fuse of a three-phase motor circuit.

Having thus described my invention, what I claim is:—

A tripping device comprising a rectangular casing, a plurality of tubes extending through the bottom of the casing at right angles thereto and having their lower ends closed, the upper ends of the tubes being flanged and spaced from the top of the casing on the interior thereof, collars secured to said tube within the casing and engaging the bottom of said casing whereby the tubes are supported, nuts fixed in the top of the casing, longitudinally bored members threaded through said nuts and projecting into the upper ends of the tubes, a headed pin slidable through each of said bored members, a longitudinally movable core carried within each of said tubes, a coil of wire surrounding the upper end of each tube, whereby a plurality of solenoids are formed, a bar pivoted intermediate its ends to the top of the casing, projections formed upon said bar and extending over the headed pin, and a rod connected at its lower end to one of said projections and adapted to be connected at its upper end to a circuit breaker to trip the latter.

In testimony whereof I affix my signature in presence of two witnesses.

OSCAR B. ALLGOOD.
